(57) CLAIM

The ornamental design for a component part of writing instrument, as shown and described.

DESCRIPTION

FIG. 1 is a perspective view of the invention;

FIG. 2 is a side view of the invention;

FIG. 3 is a front view of the invention;

FIG. 4 is another side view of the invention, showing the side opposite that shown in FIG. 2;

FIG. 5 is a back view of the invention;

FIG. 6 is a top view of the invention; and,

FIG. 7 is a bottom view of the invention.

The portions shown in broken lines in FIGS. 1-7 are included for the purpose of illustrating features on the writing instrument that form no part of the claimed design.

1 Claim, 7 Drawing Sheets
